SHIELD FOR BLAST FURNACES

Earl E. Moore, Gary, Ind.

Application November 22, 1940, Serial No. 366,775

5 Claims. (Cl. 266—32)

This invention relates generally to blast furnaces and more particularly to the provision of an outer spaced shell or shield therefor as a protective covering and as a means of maintaining a uniform temperature for the underlying metal jacket of the blast furnace, in order to avoid excessive strains and stresses due to widely varying differences in the temperature of different portions of the jacket, particularly in instances wherein the furnace lining has become thin from abrasion or other causes, and where a hot spot has developed in the metal jacket or shell.

In the operation of blast furnaces, where the brick lining has been reduced in thickness, the heat transferred to the outer metal jacket at such point is greater than to other adjacent portions where the normal thickness of the brick lining exists. Such uneven transfer of the heat results in widely varying temperatures of different portions of the jacket, which differences in temperatures, create severe stresses in the relatively thick steel plates in the jacket. The thickness of such plates will vary from three-fourths of an inch to an inch and a quarter. Under such conditions, if there is a sudden lowering of the temperature to which the outer jacket is subjected, as, for example, by the blowing of a heavy wind or sudden change in atmospheric temperature, stresses and strains of such an excessive and aggravated character have been known to be set up in the outer jacket as to cause cracking of the steel plates of the jacket, causing considerable damage to the furnace and necessitating the expense of replacement or repairs and otherwise jeopardizing the life of the furnace.

Various conditions within the furnace during its operation may contribute toward abrading or otherwise injuring the brick lining of the furnace, to cause, over a period of time, a reduction in the thickness thereof. One condition is known as a pillarizing effect which may be caused from a segregation of the coarser particles of the charge or burden of the furnace, along one side. This results in a more open portion of the charge presenting a zone of least resistance to passage of the gases and air, with the result that a more violent reaction takes place at this point, and if continued for a sufficient period of time, may result in damage to the lining of the furnace and a consequent reduction in thickness of the lining at such point.

One of the objects of this invention is to overcome some of the objections above set forth, and to provide a structure which will minimize the possibility of the outer metal jacket of the fur-

nace being subjected to such excessive strains, due to differences of temperature, as to cause cracking or other damage.

A further object is to provide a means of maintaining or regulating a substantially uniform temperature or rate of change thereof throughout a greater portion of the metal jacket arranged immediately adjacent the outer surface of the furnace lining, and to also provide a means whereby any selected portion of the furnace jacket may be subjected to a more intensified cooling action than other portions of the jacket under such conditions, for example, as the development of a hot spot.

15 A further object is to provide a protective shield for a blast furnace, which shield is held in spaced relation to the usual outer steel jacket, a construction being provided which is readily assembled and disassembled so that any particular horizontal section of the underlying jacket throughout the height of the blast furnace may be readily accessible without requiring dismantling or removal of portions of the outer shield above or below the portions to which it is desired to have access. As a structural feature, it is a purpose to minimize the necessity for use of rivets, welding, or other means of effecting permanent connections.

20 A further object is to provide for a blast furnace an enveloping substantially cylindrical air chamber surrounding the blast furnace, in which chamber heating or cooling of the steel jacket of the furnace may be effected by transmission of heat by either convection, conduction or radiation, as desired, and to further provide means for rendering readily accessible any particular portion of the outer surface of the conventional steel jacket of the blast furnace so that, if desired, temperature readings may be made at

25 30 35 40 45 50

any such points as reflecting, in a comparative sense, the temperatures within the furnace at such zones, or as indicating the relative thickness of the lining at such zones, as compared with other sections. The provision of an accessible confined air space adjacent the jacket about the furnace enables temperature readings to be more readily and accurately made than under conditions where the jacket is subjected to direct exposure to the outer atmospheric conditions. An enveloping chamber for the furnace of the above character may have various applications and utilities by connecting the upper or lower portions thereof with various sources of air, gas, or liquid supply at either the point of entry or discharge of the furnace. Conditions are favor-

able in high tower-like chambers of this character for affording larger areas for contact reactions to effect physical or chemical changes in gaseous or liquid products.

Other objects and advantages may be apparent from the following description.

The invention will be better understood by referring to the following drawings showing one preferred form for purposes of illustration, but not for limitation, as it is understood that various changes and modifications in detail of certain portions may be made without departing from the essential features of the invention.

In the drawings:

Figure 1 is an elevation view of the blast furnace, partly in section, and indicates in dotted line the manner in which the furnace lining may be impaired;

Figure 2 is a transverse section of the blast furnace taken on the line and looking in the direction of the arrows II-II of Figure 1, and shows the annular air chamber enveloping the blast furnace together with the shield spacing and supporting means, and the air conditioning and jacket cooling means in said chamber;

Figure 3 is a fragment in vertical section looking in the direction of the arrows and taken on the line III-III of Figure 2, showing particularly one plate of one frusto-conical section of the outer shield, together with the supports for the outer plate including a short length of an I-beam spacing member, and L-shaped channel ring members; there is also shown a water pipe for cooling;

Figure 4 is a fragment in vertical section looking in the direction of the arrows and taken on the line IV-IV of Figure 3, and more clearly shows the relative position of the spacing member—such as a short I-beam section—and the manner of securing the ends of sections of the encircling L-channel on the flanges at one end of the I-beam;

Figure 5 is a fragment in vertical section looking in the direction of the arrows and taken on the line V-V of Figure 4, and more clearly shows the spring clip means for detachably mounting the plates upon the vertical flange of the encircling supporting rings of the L-channel bars; and

Figure 6 is a fragment in vertical section looking in the direction of the arrows and taken on the line VI-VI of Figure 4 and shows more clearly the arrangement of the sag-rods which serve as a means of distributing and transmitting a portion of the weight of the plate load upon the channel rig members to the outer conventional jacket encasing the lining of the blast furnace.

In the illustrative form, a blast furnace is shown as including a conventional bosh and hearth portion 1, at the bottom portion thereof (a fragment of which is shown by broken lines). Such portions are supported in the conventional manner on columns 4, which are shown also as supporting a portion of the conventional mantle of the furnace, and also a section of the water draining troughs WT for conducting the cooling water discharged from the various cooling plates of the furnace. The upper frusto-conical stack portion of the furnace is indicated generally by the reference character 3 and is shown as including the conventional refractory brick lining 5 and the outer steel jacket or shell 6 encasing the lining.

The usual reenforcing steel bands 7 are shown.

5 A portion of the refractory lining which may have been impaired, due to any one of a number of causes, is indicated at 8 which shows a portion of the furnace lining of reduced thickness, at which point a greater portion of the heat is conducted through the lining of reduced thickness to the outer steel shell, which may result in a "hot spot" at such point 9, if heated for a sufficient period of time, or if the thickness of the lining is further reduced.

10 In the event of the formation of hot spots in the steel jacket of the furnace it may be possible to continue operation of the furnace and prevent the intense heat in the jacket from burning through or destroying the jacket at the hot spot, by applying a stream of water at the hot spot in order to reduce the temperature of the metal jacket at that point. A temporary lining may be formed within the furnace adjacent the hot spot, by the fused ore that passes by such spot.

15 As shown in the drawings, the outer shell designated generally by reference character 10 extends from top to bottom throughout the height of the furnace and is spaced from the jacket so as to provide an enveloping annular space 11 between the jacket and the outer shell. The shell is shown as comprising a plurality of truncated cone sections, one such section being generally designated as 13 (see Figure 1). The sections are so disposed that overlying sections assume a slight telescoping relation, with the lower portion of one section overlapping slightly the upper portion of the section immediately below. This relation is clearly shown in Figure 1 and also in Figures 3 to 6.

20 Each frusto-conical section in turn includes separate plates 12, having their vertically disposed edges arranged in slightly overlapping relation so that any separate plate may be independently positioned and removed, in order to afford access to a corresponding portion of the jacket, without disturbing any substantial number of adjacent plates. As a means of supporting the plates 12, a series of ring members 15 are provided, each of varying diameter (for instance when used in connection with a frusto-conically shaped stack). Means for positioning said rings on the jacket serve also as a spacing means between the jacket and the outer shell.

25 The ring members designated generally as 15 circumscribe the furnace and are held in spaced relation from the jacket by a suitable means. As shown in the preferred form (see Figures 3 and 4), a relatively short section or piece of an I-beam designated generally as 14, is employed, having its web portion 14^c disposed in a vertical plane. The flanges 14^a at one end of the I-beam serve as a base or footing engagement with the outer face of the jacket and preferably are welded thereto although other suitable means of connection may be employed. Such base 14^a transmits the downward and radial stress from the plate load on the spaced ring frame members 15 to the jacket 6.

30 The flanges 14^b at the opposite or outer end of the web portion 14^c of the I-beam serve as a convenient means of supporting the encircling rings designated generally as 15, by a suitable fastening means such as a bolt and nut connection 16. The bolt and nut connection serves as a convenient means for facilitating assembly and positioning of the ring members 15 relative the I-beam spacing member 14, particularly when the ends of the ring member 15, or sections thereof, 35 are secured to the flange portions 14^b on opposite

sides of the web 14^c . This structure and arrangement is more clearly shown in Figure 4. The ring members 15 are preferably formed in sections in order to facilitate handling in assembly, and also in fabrication thereof. The desirability of this becomes apparent when it is considered that blast furnaces are of substantial size, some having a height from the base of the mantle to the top of the charging dome of 75 feet, and an outside diameter at the shell of 35 feet. In the preferred form shown, each ring member 15 is formed of four sections and the I-beam spacing members are disposed at points spaced 90 degrees apart about the circumference of the furnace, and at the point where the ends of the quadrant sections of the rings are connected together through the medium of the outer flange 14^b of the I-beam. In this manner, the I-beam section conveniently serves a double function of a spacing member and a connector. By virtue of the connection of the outer flange 14^b with the ends of the sections of the ring member, such flange portion of the I-beam becomes a part of the ring. It is, of course, understood that if desired, other suitable means of connection between the I-beam and the ring members or sections thereof may be employed, such, for example, as a weld connection. The connection with the ring members may also be made at points other than the ends of the sections of the ring. Where the I-beam spacing member is employed in connection with a portion of the blast furnace, which is tapering on the outside, as, for example, when of frusto-conical contour, when the ring members are connected to the outer web of the I-beam, the tapering contour of the jacket 6 of the furnace itself serves as a means for maintaining the I-beam and the loaded ring members connected therewith in proper relative position. However, a welded connection between the inner flange 14^a of the I-beam and the jacket 6 prevents any tendency toward relative movement of the parts.

As shown in section in Figures 3, 5 and 6, the ring members 15 are formed preferably of L-shaped channel members having one of the flanges 15^a in a substantially upright position, and the other flange 15^b substantially vertical and extending within the space 11 formed between the outer steel shell 10 and the inner jacket 6 . It is with such upstanding flange of the ring member, that the connection of the outer flange 14^b of the I-beam is made. Such upstanding flange 15^a of the L-channel serves also as a convenient means for establishing a detachable connection with a series of outer plates 12 which form the main outer steel shell designated generally as 10 .

A preferred means for effecting a detachable mounting for the plates 12 upon the ring member 15 is more clearly shown in Figure 5. Preferably, the plates 12 are supported on ring sections which are vertically spaced from each other and are disposed at points adjacent the upper and lower edges of the plate 12 , but at distances within or between overlapping portions of plates of adjacent frusto-conical sections, above and below. As a means of affording a detachable mounting of the plate 15 upon the vertical flange portion 15^a of the ring member there is provided a clip member designated generally as 17 , having an upper portion thereof 17^a , secured to the inner face of the plate 12 by rivets 18 or other suitable means. The lower portion 17^b of the clip is bent outwardly to form an offset spaced portion adapted to receive the upstanding flange 15^a of

the ring member. As indicated in Figure 1, three of such detachable spring-like clip connectors 17 are provided for each plate, two such clips being provided for connection with the upper ring member of a frusto-conical section, said clips being disposed adjacent the side edges of the plate, and one clip being disposed near the lower portion of the plate and adapted to slidably engage the upstanding flange 15^a of the lower ring member of the section. It is, of course, understood that a different number of clips for a plate, and various disposition and arrangement of the detachable clips, may be employed. Modified forms of clips may also be used for effecting the detachable plate connection.

For a blast furnace of the dimensions above referred to, plates having a length of approximately 7 feet and a width of from 3 to 4 feet, have been found satisfactory as a convenient size to handle. An overlapping at the side edges of the plate of approximately 4 inches and an overlapping of 3 inches at the top and bottom edges with plates of adjacent frusto-conical sections of the furnace has been found satisfactory.

In order to provide an additional strengthening of and support for the loaded quadrant sections of the ring members 15 , intermediate their connections at the ends with the I-beam 14 , there may be provided U-channels 19 at suitably spaced intervals (see Figure 2), which are interposed between the upstanding flange 15^a of the ring member, and the jacket 6 . Additional means may also be provided to restrain any tendency of the quadrant ring sections to sag at points intermediate its end connections with the I-beam. For this purpose, there may be employed sag-rods 23 (see Figures 4 and 6), the upper end of which may be detachably secured to a boss or flange secured in any suitable manner, as, for example, by welding to the jacket 6 ; and the lower end of the sag-rod 23 may be detachably connected to a portion of the upper ring member of a frusto-conical section, which connection with the ring may be made in any suitable manner. As shown, short lugs or arms are spaced apart a distance sufficient to receive the sag-rod therebetween, such lugs being securely fixed in any suitable manner, as by welding to the ring section. If desired, the lower end of the sag-rod may be detachably secured to the ring member 15 by providing suitable apertures in the horizontally disposed flange 15^b of such ring member to permit a threaded end of the sag-rod to pass therethrough to receive a washer and nut. Preferably, the boss or flange connector for the upper end of the sag-rod is disposed on the jacket at a point adjacent, and preferably above, the upper portion of the frusto-conical section for which it serves as a support. Such a disposition facilitates the assembly of the parts by permitting access to parts, and particularly the positioning and tightening of the sag-rods.

As a means of controlling or regulating the temperature of the air within the space 11 between the jacket 6 and the outer shell 10 , and as a means of cooling the entire outer surface of the blast furnace jacket by a fluid cooling medium, or in order to apply the liquid cooling medium to a selected portion of the outer jacket, such, for example, as to a hot spot, there is provided a series of water jets arranged at suitable points throughout the height of the furnace. As shown (see Figures 1, 2, 3 and 5), a water pipe 20 having suitable jets or outlets therein is shown supported in any suitable manner, such, for ex-

ample, as by a lug and clamp connection, to the jacket of the furnace. As shown in Figure 1, three ring-like pipe sections are disposed at three different elevations throughout the height of the furnace. It is understood that various other arrangements and disposition of the piping for delivering the fluid cooling medium may be employed.

In addition to the employment of liquid cooling medium for cooling any hot spots that may develop in the furnace jacket, the cooling medium may be employed to condition the air within the space to induce circulation of air within the space. Due to the height of the confined air column between openings at the top and bottom, and due to differences in temperature that may exist, conditions are such that a substantial flow or draft of air may be induced. In this respect the outer shell enables a draft or circulation somewhat comparable to a flue-like effect to be obtained.

Under certain conditions, an enveloping annular chamber of the character herein disclosed may be adapted to various uses and purposes for treating and conditioning gases or liquids conducted therethrough, by connecting the upper, intermediate, or lower portions thereof with various sources of air, gas, or liquid supply at either the point of entry to or discharge from the blast furnace or other chamber in a conventional manner, well known in the art. In addition to the favorable conditions existing in a high shell-like annular chamber, serving as a means for effecting large contact areas throughout substantial distances for effecting transfer or interchange of thermal heat energies, such conditions are also favorable for utilization in recovery processes of by-products.

While one preferred form of invention has been shown for purposes of illustration, modifications in detail of various parts may be made without departing from the spirit and scope of this invention, as defined in the appended claims.

I claim:

1. In a blast furnace having a frusto-conical stack portion and a metal jacket therefor encasing the refractory wall and lining thereof, an outer cooling shell spaced from said jacket, and spacing means for supporting said shell in spaced relation to said jacket whereby an air space is formed between said jacket and shell, said shell spacing means including a series of spaced supporting rings arranged to form a frusto-conical frame, each ring being independently supported on said jacket, said shell being of frusto-conical form and including a plurality of frusto-conical sections having their upper and lower edges in overlapping relation with adjacent sections, each section including a plurality of plates arranged in overlapping relation, each plate being separately independently, detachably mounted on said frame, whereby any one of the plates of the shell may be removed independently.

2. In a blast furnace having a frusto-conical stack portion and a metal jacket therefor encasing the refractory wall and lining thereof, an outer cooling shell spaced from said jacket, and spacing means for supporting said shell in spaced relation to said jacket whereby an air space is formed between said jacket and shell, said shell spacing means including a series of spaced supporting rings arranged to form a frusto-conical frame, each ring including an L-channel and being independently supported on said jacket, said shell being of frusto-conical form and including

a plurality of frusto-conical sections of different sizes and having their upper and lower edges in overlapping relation, each section including a plurality of plates, each plate being separately 5 independently, detachably mounted upon the L-channel of said ring, whereby any one of the plates of the shell may be removed independently to permit access to an underlying portion of the jacket without disturbing any substantial 10 number of adjacent plates.

3. In a blast furnace having a frusto-conical stack portion and a metal jacket therefor encasing the refractory wall and lining thereof, an outer cooling shell spaced from said jacket, 15 whereby an air space is formed between said jacket and shell, said outer shell including a plurality of frusto-conical sections arranged in overlapping, telescoping relation, each section including a separable and independent unit, capable of being assembled or disassembled independently of the other sections, each section including a plurality of spaced rings of different diameters independently carried by the jacket, supporting and spacing means for holding each 20 of said rings in spaced relation to the jacket adjacent the upper and lower edge of each section, said supporting and spacing means including a relatively short I-beam section having the web thereof disposed in vertical plane, the flanges 25 at one end of said I-beam section resting on the jacket and the flanges at the other end of said I-beam section engaging the rings, each ring including a plurality of arcuate sections of L-shaped channel presenting one of its flanges in 30 a substantially vertical plane and being so disposed as to lie adjacent to and be secured to the flange at one end of said spacing I-beam section, and securing means for connecting the outer flanged end of said spacing member and one of the flanges of said ring member, each frusto-conical section also including a plurality of plates being connected to said rings by a hooked clip connection adapted to engage the vertical flange 35 of said ring, whereby any horizontal section of the shell corresponding with any one of the frusto-conical circular sections or any plate of said section may be removed independently without requiring disassembly of other sections or other plates, and sag-rod connectors, one end 40 of said sag-rod being connected to the jacket and the other end being connected to the spaced ring member on which the plates are supported.

4. In a blast furnace having a stack portion and a metal jacket therefor encasing the refractory wall and lining thereof, an outer shell spaced from said jacket, whereby an air space is 45 formed between said jacket and shell, said outer shell including a plurality of sections, each section including a plurality of spaced rings carried by the jacket, supporting and spacing means for holding said rings in spaced relation to the jacket, said supporting and spacing means including a relatively short I-beam section, each ring including a section of a flanged channel member presenting one of its flanges in a substantially vertical plane, and securing means for connecting the outer flanged end of said spacing member and one of the flanges of said ring member, each section also including a plurality of plates, and connecting means for detachably 50 mounting and securing said plates in position upon said ring section.

5. In a blast furnace having a frusto-conical stack portion and a metal jacket therefor encasing the refractory wall and lining thereof, an

outer cooling shell spaced from said jacket, whereby an air space is formed between said jacket and shell, said outer shell including a plurality of frusto-conical sections arranged with their upper and lower edges in overlapping telescoping relation, each section including a separable and independent unit, a plurality of spaced rings of different diameters, supporting and spacing means for holding said rings in spaced relation to the jacket, said supporting and spacing means including a relatively short I-beam section, each ring including a section of a flanged channel member presenting one of its flanges in a substantially vertical plane, and securing means

5 for connecting the outer flanged end of said spacing member and one of the flanges of said ring member, each frusto-conical section also including a plurality of plates adapted to engage the vertical flange of said ring whereby any horizontal section of the shell corresponding with any one of the frusto-conical circular sections may be removed independently in whole or in part without requiring disassembly of other sections, and sag-rod connectors interposed between the jacket and the ring members on which the plates are supported.

EARL E. MOORE.
